UNITED STATES PATENT OFFICE

JOHN L. McMILLAN, OF SYRACUSE, NEW YORK, ASSIGNOR TO McMILLAN BOOK COMPANY, OF SYRACUSE, NEW YORK, A CORPORATION OF NEW YORK

VISIBLE-INDEX BINDER

Application filed April 16, 1928. Serial No. 270,423.

This invention relates to a new and improved visible index binder of the type ordinarily called ring binder.

In using a loose leaf binder it is frequently desirable to have the leaves in the binder so arranged that they will provide a visible index of the contents of the binder.

In order to accomplish this result it is necessary to have sheets which are less in width than the binder itself so that they may be positioned on the retaining rings or prongs in such a way that a portion of each sheet is exposed to view.

It is usually necessary in devices of this character to remove sheets therefrom from time to time and insert new sheets and when this is done it is usual to place the new sheet at the bottom of the binder. In order to do this it is necessary that the sheets, below the one which has been removed, should be moved upwardly so that they will be in the proper position with relation to the remaining sheets in the binder. In order to facilitate the movement of sheets back and forth in the binder, as desired, a means should be provided whereby such movement of the sheets may be made simultaneously and without the necessity of entirely removing the sheets from supporting ring or prong.

The main object of my invention is to provide a device which may be used as desired in conjunction with a binder for the purpose of permitting the transfer of sheets from one set of prongs to another while at the same time the sheets will be at all times retained on rings.

Another object of my invention is to provide a device which may be used in different parts of the binder at the user's option and which also may be used with any one of a plurality of similar binders.

Other objects and advantages relate to the size, shape and arrangement of parts all as will more fully appear from the following description taken in connection with the accompanying drawings in which:

Figure 1 is a top plan view of a binder with the prongs in the open position and with two of my devices in position, the covers of the binder being partially broken away.

Figure 2 is a section on line 2-2 of Figure 5.

Figure 3 is an end elevation of the back of my binder with the prongs in the closed position.

Figure 4 is an end elevation of the back of the binder with the prongs in the open position.

Figure 5 is a section on line 5-5 of Figure 1.

Figure 6 is a perspective view of my transferring device.

Although the exact construction of a binder with which my device may be used is not in all details material particularly as to the means by which the opening and closing of the binder is accomplished yet for the purpose of illustrating the construction of my device and the manner in which it is used in conjunction with a binder, I have here shown a binder having a back member —1— and a second back member —2— in parallel relation therewith, the two back members 1 and 2 being hingedly connected by hinges —3— and —4—. A back plate —5— is affixed to the outer longitudinal edge of member —1— and a similar back plate —6— is affixed to the outer longitudinal edge of member —2—. A top plate —7— approximately right angular in cross section is positioned on the upper surface of member —1— in parallel spaced relation to back plate —5— and being return bent on the top to register with and cover back member —5—. A similar top plate —8— is positioned on member —2— in parallel spaced relation with back plate —6—. A locking plate —9— is positioned on the upper surface of member —1— and overlaps top member —7— to secure the same in position. A similar locking plate —10— is positioned on member —2— and overlies top plate —8— to secure the same in position.

The top surfaces of top members —7— and —8— are provided with a plurality of opposed holes 11—11 in spaced relation. Prongs or arcuate rods 12—12 have one of their ends secured by welding or other convenient means in alternate holes 11—11 in each top plate —7— and —8—. The prongs —12— in top plate —7— are in staggered re-

lation to the prongs —12— in top plate —8— so that when the book is in the closed position as shown in Figure 3 the prongs 12 in top plate —7— will be intermediate the prongs 12 in top plate 8 and will register with holes 11 in top plate —8—. Similarly the prongs —12— in top plate —8— will be intermediate the prongs —12— in top plate —7— and will register with holes —11— in top plate —7—.

For the purpose of releasably securing the binder in the open or closed position I provide at the opposite ends thereof similar devices consisting of an end plate —13— secured to member —1— and carrying adjacent one edge a lug —14—. A second end plate —15— is affixed to the end of member —2— and is provided with a slot —16—. A locking member —17— is pivotally mounted in end plate —15— by means of rod —18— and is provided at one side of the pivot with an elongated slot —19— engaged with lug —14—. Locking plate —17— carries, on the other side of the pivot, a tongue —20— which extends inwardly through slot —16— and also carries an outwardly extending tab —21—. On the inner face of end plate —15— and encircling rod —18— there is positioned a coiled spring —22— having one end in engagement with tongue —20— to normally hold tongue —20— at the upper end of slot —16—. Rod —18— has one end rigidly secured to locking plate —17— and extends through member —2— carrying on its other end a locking plate —23— similar in design to locking plate —17— and coacting in a similar manner with end plates, not shown, of the same design and construction as end plates —13— and —15— just described.

The opposite ends of slot —19— are formed with recesses —24— and —25— in which lug —14— is releasably held by the action of springs —22— so that in order to move members —1— and —2— in relation to each other it is necessary to pivot locking plate —17— by means of tab —21— in order that lug —14— may be moved out of a recess and thence to the other end of slot —19—. When the book is in the closed position lug —14— is in recess —24— as may be seen in Figure 3 and when the book is in the open position lug —14— is in recess —25— as may be seen from Figure 4.

I provide between back plate —5— and top plate —7— a slide —26— abutting against the ends of prongs —12— and being provided with a plurality of tongues —27—. When the slide —26— is pushed inwardly the tongues —27— will not register with the open holes —11— in top plate —7— but when the slide —26— is pulled outwardly as shown in Figure 2 the tongues —27— will register with the open holes 11 extending approximately through the center of the open holes

—11—. The purpose of tongues —27— on slide —26— will be hereinafter described.

My transferring device consists of an arcuate rod —28— composed of two substantially equal portions —29— and —30— connected by a central angular portion whereby the end portions are offset so as to be in two separate parallel planes and of a size and shape conforming to the shape and size of prongs —12—. The degree to which end portion —29— is offset with relation to end portion —30— is such that when end —30— is inserted into a hole —11— in top plate —7— the opposite end —29— will be in a position to register with one of the holes —11— in top plate —8— that are nearest opposite said first hole.

I provide in the ends of arcuate rod —28— slots —31— and —32—. When arcuate rod —28— is in position in holes —11— and slide —26— is pulled outwardly a tongue —27— will register with a slot as —32— to lock the arcuate rod —28— in position. A second slide, 26, is positioned between back plate —6— and top plate —8— for coaction with the slots as —31— in arcuate rod —28— when the latter is in position in a hole —11— in top plate —8—.

For the purpose of providing the binder with a protective and ornamental covering I provide on member —1— back strips —33— and —34— and on member —2— back strips —35— and —36—.

It will be understood that my binder is provided with the usual pair of opposed covers as —37— and —38— hinged connected to back plates —5— and —6— respectively.

When it is desired to use my device for changing the relative position of sheets in the binder I depress one of the tabs —21— to release locking plates —17— and I then open the binder into the position shown in Figure 1. I then place one of my arcuate rods —28— in position with one end extending through a hole as —39— through leaf —40— (shown in Figure 1 partially broken away) and into a hole —11— in top plate —7—. I then place the opposite end of arcuate rod —28— into a hole —11— in top plate —8—. Slides 26—26 are then pulled outwardly in the manner heretofore described to lock arcuate rod —28— in position.

In order to facilitate the transfer of a sheet —40— it is preferable that a second arcuate rod —28— be placed through another hole —39— in sheet —40— and locked in position in the manner just described.

As perhaps may best be seen from Figure 1 sheet —40— may then be pulled upwardly on prongs —12— and arcuate rods —28—. When sheet —40— leaves the ends of prongs —12— it will be carried diagonally across the binder on the guiding means furnished by arcuate rods —28— so that when it is in position to have prongs —12—, on the opposing

back member of the binder, enter holes —39— the sheet will have moved laterally of the binder into the position shown in dotted lines on Figure 1. The arcuate rods —28— may then be removed from the binder and the binder closed.

It will be understood that as many sheets may be moved in one operation as desired, and it will also be understood that the sheets 10 may be moved longitudinally of the binder in either direction as desired depending upon the side of the binder the sheet is placed on when the transferring operation is begun.

It will also be understood that the distance 15 a sheet is to be moved in one operation may be varied as desired by the spacing and shape of the prongs —12— of the binder and the arcuate rods —28—, for although I have shown and described a specific structure and association of parts I do not desire to restrict myself 20 to the exact size, shape or relation of parts as various changes may be made within the scope of the appended claims.

What I claim is:

25 1. In a device of the class described, a pair of opposed back members hingedly connected together, a member carrying a plurality of spaced prongs and having apertures between adjacent prongs affixed to each of the back 30 members and an arcuate rod having relatively laterally offset end portions and having one end removably positioned in an aperture in one prong-supporting member and having its other end similarly positioned in the other 35 prong-supporting member.

2. In a device of the class described, a pair of opposed back members hingedly connected together, a member carrying a plurality of spaced prongs and having apertures between 40 adjacent prongs affixed to each of the back members, an arcuate rod having relatively laterally offset end portions and having one end adapted to be releasably secured in an aperture in one prong-supporting member and having its other end adapted to be similarly 45 releasably secured in the other prong-supporting member, and means for releasably securing the ends of the arcuate rod in the prong-supporting members.

50 3. In a device of the class described, in combination a loose leaf binder having opposed back members, an arcuate rod having relatively laterally offset ends portions and means for releasably securing one end of the 55 rod on one of the back members and the other end on the other back member.

In witness whereof I have hereunto set my hand this 9 day of April, 1928.

JOHN L. McMILLAN.
